UNITED STATES PATENT OFFICE.

FRED W. HARGRAVE, OF SOUTH RIVER, AND JAMES A. WHEELER, OF SOMERSET COUNTY, NEW JERSEY, ASSIGNORS TO WILLIAM T. ELKINTON, OF PHILADELPHIA, PENNSYLVANIA.

FIREPROOF DOOR.

1,163,914.

Specification of Letters Patent. Patented Dec. 14, 1915.

Application filed January 29, 1914. Serial No. 815,141.

To all whom it may concern:

Be it known that we, FRED W. HARGRAVE, a resident of South River, in the county of Middlesex and State of New Jersey, and 5 JAMES A. WHEELER, a resident of the county of Somerset, in the State of New Jersey, both citizens of the United States, have invented certain new and useful Improvements in Fireproof Doors, of which the following is a specification.

This invention relates to fireproof doors of that class which are constructed of an artificial fireproof lumber or composition and metallic elements, and it has for its object 15 to provide a simple and improved fireproof door of this character which will possess advantages in point of lightness and strength, resistance to strains, effectiveness and general efficiency, and which will furthermore 20 be simple and inexpensive in construction and can be manufactured with facility and economy.

In the drawings Figure 1 is a face view of the door embodying our improvements, 25 partly broken away to show the interior construction. Fig. 2 is a detail vertical cross-section, on an enlarged scale, taken on the line $x-x$, Fig. 1. Fig. 3 is a detail horizontal cross-section, on an enlarged scale, 30 taken on the line $y-y$, Fig. 1.

Corresponding parts in all the figures are denoted by the same reference characters.

Our invention comprises in its main characteristics an exterior metallic casing or 35 sheathing which incloses an internal body structure formed of an artificial fireproof lumber or composition. The elements of the main body portion constituted by said internal structure within the outer sheathing are 40 formed of a rigid non-metallic composition of low heat conductivity and undeformable by heat, and the artificial fireproof lumber or composition may be of any suitable material, but we prefer to use for this purpose 45 the composition which is commercially known as "alignum" and which is constituted by a suitable filler including asbestos and combined with a fireproof binder to produce a plastic substance which is molded 50 into shape and compressed and dried in a rigid structure.

Referring to the drawings, 1 designates the exterior casing or sheathing, which forms the surface of the door and extends over the area of the same at the sides and 55 edges thereof. This metallic casing or surface is, in practical manufacture, constituted by two corresponding half-parts or sections, 2-2, each of which halves comprises a thin metallic plate or sheet, 3, bent 60 into proper angular contour in cross-section and forming the face of the door and half of the edge portion thereof. The metallic casing or sheathing plates 3 thus respectively form channels or molds within which 65 are held the non-metallic and fireproof composition elements which constitute the internal body structure of the door.

The improved construction and arrangement, as comprised in our present invention 70 and improvements, enables the molding, in practical and economical manufacture, of the internal body composition structure within the mold formed by the metallic sheathing plates 3 of the half-sections of the 75 exterior casing 1. Thus, in manufacture, the half-section molds or channels constituted by the metallic sheathing plates 3 are placed and braced in a suitable press, and the composition forming the internal body 80 structure is molded therein in a plastic state, with the employment of suitable cores to produce the desired molded contour, and is compressed and dried in a rigid structure.

To facilitate the retention of the internal 85 composition, during the molding operation and after it is compressed and dried in position, the edges of the plate 3 which are positioned at the edge portion of the door, as at 4, are turned inwardly at an angle to 90 form a projecting retaining flange, as at 5.

The internal body composition has, in its preferred molded form, a relatively-thin base portion, 6, extending against and over the area of the face portion of the sheathing plate 3 which forms the side surface of the door, and thickened edge portions, as at 7, forming continuous blocks or bars extending around the edge portion of the sheathing plate 3 which extends at the edge 95 of the door, whereby an interior open area or space, as at 8, will be formed interiorly 100

of the door and extend substantially throughout the entire interior body area thereof, for purposes of lightness and economy.

5. The two half-sections 2-2 of the casing structure 1 have their inner surfaces, which are constituted by the faces of the thickened-edge block or bar portions 7 of the internal composition body structure, abutted and secured together, adhesively or otherwise, as at 9, to produce the complete door structure, after the respective half-sections 2-2 have been constructed or produced as above described.

15. In the internal open area or space 8, bracing means are preferably provided between the side portions of the door structure, and the preferred construction for this purpose comprises bars or blocks, as at 10, extending continuously between the top and bottom of the door and in parallel position at suitable intervals. These bracing bars or blocks are thus, in the half-sectional construction as herein shown, constituted by two half-sections 11-11, respectively carried by the half-sections 2-2 of the casing structure and having their inner faces abutted and secured together, adhesively or otherwise, as at 12.

30. In the practical manufacture, in which the internal composition body structure 6-7 is molded within the sheathing plate 3 of the half-sections 2 of the exterior casing 1, the half-sections 11 of the continuous bracing blocks or bars 10, are likewise molded in position within the half-sections 2 of the casing structure, in a plastic state, with the employment of suitable cores to produce the desired molded contour, and are 35 compressed and dried in a rigid structure. The half-sections of the continuous internal bracing bars or blocks thus have their base upon the relatively-thin base portion 6 of the internal composition body structure and 40 project therefrom and extend between the thickened edge portions 7 thereof at the top and bottom of the door, and divide the internal open hollow area 8 into a plurality of open spaces. Said internal bracing bars 45 or blocks are likewise of the non-metallic fireproof composition corresponding to the composition of the internal body structure, and under some conditions of manufacture they may be molded or formed separately 50 from the internal composition body structure and secured in connection therewith and in proper position adhesively or in any other suitable manner. Our improved door structure is also preferably provided internally 55 with blocks, as at 14, likewise formed of the non-metallic fireproof composition as herein referred to, and located within the internal area or space 8 at suitable points, which blocks provide strong and effective 60 means for the butt in the attachment of the 65

hinges, locks, or other supplementary devices of the door. Said blocks 14 are adhesively or otherwise secured in position against the thickened edge-portions 7 and between the base portions 6 of the internal 70 composition body structure.

It will be understood that all the various parts of the door structure, as hereinbefore described, may be secured in connection adhesively or by the employment of screws or 75 bolts at any desired point, as the rigid non-metallic fireproof composition herein constituting the main body structure can be worked or will receive nails or screws in the same manner as ordinary lumber.

80. The outer faces of the casing 1 are suitably finished, in imitation of grained wood or as otherwise desired, and may be ornamented to impart any desired effect or characteristics to the door surface. For instance, ornamental molding strips may be secured upon said faces, to produce panel effects or other ornamental irregularities of the surface. It will be also understood that the door structure may be made up of a plurality of sections constructed and embodying the general features as hereinbefore described, with intervening arrangements of panels or with open spaces for the insertion 85 of glass panels.

95. The advantages of our improved door will be readily understood by those skilled in the art to which the invention appertains. The main structure is constituted by the rigid non-metallic composition of low heat conductivity and undeformable by heat, and is therefore resistant to the action of extreme heat to maintain the normal conditions of the door structure and preclude the breaking down of the same under the action of 100 heat. In this connection, the office of the thin metallic surfacing or sheathing which forms the exterior surface of the door is to preclude impairment of the finished surface by dents or other conditions of usage or wear, 105 and also to serve as a mold in which the non-metallic fireproof composition constituting the internal body structure can be molded in plastic condition into its structural shape 110 and compressed and dried in a rigid structure, thus facilitating lightness and economy in manufacture. Under the action of extreme heat, the exterior metallic casing or sheathing is effectively protected against deformation inasmuch as it is sustained at all 115 points by the inclosed composition body structure which conforms to the same and which is non-metallic and of low heat conductivity and undeformable by heat.

120. The improved construction, as comprised in our invention, provides a very simple and light door structure which is thoroughly braced against any strains or conditions of use, which can be easily and economically manufactured, and which will possess in 125 130

maximum degree all the desired fireproof characteristics and strength.

We do not desire to be understood as limiting ourselves to the detail construction 5 and arrangement of parts as herein shown and described, as it is manifest that variations and modifications therein may be resorted to, in the adaptation of our invention to varying conditions of use, without departing from the spirit and scope of our invention and improvements. We therefore reserve the right to all such variations and 10 modifications as properly fall within the scope of our invention and the terms of the 15 following claims.

Having thus described our invention, we claim and desire to secure by Letters Patent:

1. An improved fireproof door, comprising an exterior casing or sheathing constituted by corresponding half-sections each 20 consisting of a metallic plate forming the surface of the door and extending over the side and edge portion thereof and an internal body structure inclosed within said sections of the metallic casing and formed of a rigid non-metallic composition of low heat conductivity and undefeatable by heat, said half-sections being secured together with their inner faces abutting and said internal composition body structure being in 25 its main area of less thickness than the half-section of the door and forming an interior open area or space between the portions of the metallic sheathing which extend over the 30 sides of the door.

2. An improved fireproof door, comprising an exterior casing or sheathing constituted by corresponding half-sections each 40 consisting of a metallic plate forming the surface of the door at the side and edge portion thereof and an internal body structure inclosed within said sections of the metallic casing and formed of a rigid non-metallic composition of low heat conductivity and 45 undefeatable by heat, said internal composition body portion of the half-sections of the exterior metallic casing having a base portion extending against the side face of the sheathing plate and thickened edge portions 50 forming continuous blocks or bars extending around the edge portion of the sheathing plate, and the half-sections of said casing being secured together with the faces of said thickened edge portions abutting, whereby an interior open area or space 55 is formed.

3. An improved fireproof door, comprising an exterior casing or sheathing constituted by corresponding half-sections each 60 consisting of a metallic plate forming the surface of the door at the side and edge portion thereof and an internal body structure inclosed within said sections of the metallic casing and formed of a rigid non-metallic composition of low heat conductivity and 65

undefeatable by heat, said internal composition body having an interior open area or space and said half-sections being secured together with their inner faces abutting, and bracing bars or blocks extending in the internal area or space of the composition body structure of said half-sections of the casing and having their inner faces abutted, said bars or blocks being formed of a rigid non-metallic composition of low heat conductivity and undefeatable by heat. 70 75

4. An improved fireproof door, comprising an exterior casing or sheathing constituted by corresponding half-sections each 80 consisting of a metallic plate forming the surface of the door at the side and edge portion thereof and an internal body structure inclosed within said sections of the metallic casing and formed of a rigid non-metallic composition of low heat conductivity and undefeatable by heat, said internal composition body portion of the half-sections of the exterior metallic casing having a base portion extending against the side face of the sheathing plate and thickened 85 edge portions forming continuous blocks or bars extending around the edge portion of the sheathing plate, and the half-sections of said casing being secured together with the faces of said thickened edge portions 90 abutting, whereby an interior open area or space is formed, and bracing bars or blocks extending within said interior open area or space of the half-sections of the casing and between the thickened edge portions of said 95 internal composition body and having their inner faces abutted, said bars or blocks being formed of a rigid non-metallic composition of low heat conductivity and undefeatable by heat. 100 105

5. An improved fireproof door, comprising an exterior casing or sheathing forming the surface of the door at the side and edge portion thereof, said casing being constituted by corresponding half-sections each 110 consisting of a metallic plate forming a mold within which a non-metallic composition of low heat conductivity is molded into shape and compressed and dried in a rigid structure undefeatable by heat, said composition 115 forming an internal body structure inclosed within the half-sections of said metallic casing and being in its main area of less thickness than the half-sections of the door and said half-sections being secured together 120 with their inner faces abutting.

6. An improved fireproof door, comprising two corresponding half-sections each 125 having an internal body structure formed of a rigid non-metallic composition of low heat conductivity and undefeatable by heat and an exterior metallic casing which carries and incloses said body composition and forms the external sheathing or surface of the structure, said external sheathing being 130

constituted by a casing mold within which
said internal composition body mass is com-
pressed and molded into shape and dried in
a rigid structure, the corresponding half-
5 sections being secured together with their
inner surfaces abutting:

In testimony whereof we have signed our

names in the presence of the subscribing wit-
nesses.
